UNITED STATES PATENT OFFICE.

MAX MCKINNEY, OF NEW YORK, N. Y., ASSIGNOR OF FIVE-EIGHTIIS TO
CHARLES M. DOBSON, OF SAME PLACE.

DESIGN FOR A TOY.

SPECIFICATION forming part of Design No. 30,868, dated May 23, 1899.

Application filed May 10, 1898. Serial No. 680,322. Term of patent 31 years.

To all whom it may concern:

Be it known that I, MAX MCKINNEY, a citizen of the United States, residing in the city, county, and State of New York, have invented and produced a certain new and original Design for Toys, of which the following is a specification.

The new design relates to toys.

My present invention provides a new and original shape for toys.

The new design is shown in the accompanying drawing, which is a perspective view of a toy.

In the drawing, A represents a spherical body; B, a small cylindrical downward projection therefrom; C, a short cylindrical portion at the extremity of the projection B, which portion has longitudinal flutes or serrations; D, a relatively large square projection at the upper side of the sphere A and diametrically opposite the projection B; E, a plurality of squares on the end of the projection D; F, recesses between such squares, and G irregular waving members from the end of the projection D.

The body A is a smooth sphere. The projection B is relatively small and of smooth cylindrical exterior. The member C is comparatively short, substantially cylindrical, and of slightly greater diameter than the projection B. The projection D is relatively large and of square or rectangular cross-section. The recesses F are parallel with its longitudinal axis and have a depth equaling a small portion of its length. The members G are wavy and irregular projections from the projection D, extending outwardly and upwardly therefrom at approximately right angles to each other.

What I claim is—

The design for a toy as herein shown and described.

In witness whereof I have hereunto signed my name in the presence of two subscribing witnesses.

MAX MCKINNEY.
